STYLUS GUIDE DEVICE

Joseph Lapir, Brooklyn, N. Y.

Application April 15, 1948, Serial No. 21,225

5 Claims. (Cl. 274—13)

1

This invention relates to new and useful improvements in means for making sound records.

More specifically, the invention proposes the construction of a means for making sound records characterized by a device for attachment to a conventional phonograph having a turntable for a standard record upon which a record blank for be cut is adapted to be mounted in a manner to rotate with the turntable.

Still further it is proposed to characterize the new attachment by a universally supported horn having a sound sensitive recording stylus means with a vertical sound box. It is proposed to clamp a pair of arms on to the edge portions of the sound box. It is further proposed to mount the follower means on said arms for following the groove of the standard record and indirectly moving the said stylus means to cut a groove and a recording in said record blank.

The invention makes use of a bridge mounted between the outer ends of said arms, a stud turnably mounted on said bridge, and said follower means being mounted on said stud. It is proposed that the follower means include brush bristles for engaging the groove of said standard record.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a plan view of means for making sound records, constructed in accordance with the invention.

Fig. 2 is a fragmentary elevational view of Fig. 1.

Fig. 3 is a fragmentary sectional view taken on the line 3—3 of Fig. 1.

Fig. 4 is a fragmentary vertical sectional view taken on the line 4—4 of Fig. 1.

Fig. 5 is a fragmentary enlarged vertical sectional view taken on the line 5—5 of Fig. 1.

Fig. 6 is an enlarged transverse sectional view taken on the line 6—6 of Fig. 5.

Fig. 7 is a fragmentary sectional view similar to Fig. 5 but illustrating a modified form.

The means for making sound records, in accordance with this invention, is used in combination with a phonograph 10 having a turntable 11 for a standard record 12. This record 12 has the usual blank central area upon which is placed the new blank record 13. This blank 13

2

may be adhesively attached to the record 12 so as to turn with the record. However, the adhesive must be of a type which will permit the record 13 to be removed when completed. The details of the phonograph 10 and the driving mechanism of the turntable 11 will not be given in this specification as they form no part of the invention.

The new record making means includes a horn 14 which is universally supported on a bracket 15 which is mounted on the phonograph 10 near the turntable. This bracket 15 turnably supports a stud 16 which connects with a yoke 17, in turn pivotally connected by a pintle rivet 18 with lugs 19 on the bottom of the horn 14. The rear end of the horn 14 is equipped with a sound sensitive recording stylus means 20 having a vertical sound box. The details of this stylus means will not be given in this specification since this is old structure.

A pair of arms 21 is clamped to the edge portion of the sound box 20. The arms 21 have their rear ends formed with clamp portions 22 provided with clamp screws 23 by which the arms may be clamped as stated. Each arm 21 is formed from a pair of telescoping sections 21^a and 21^b which may be locked in adjusted positions by the set screws 24.

A bridge 25 is mounted across the outer ends of the arms 21, and more specifically, across the outer ends of the sections 21^a. A stud 26 is turnably mounted on the bridge 25. Follower means is mounted on this stud 26 and includes brush bristles 27 for engaging the grooves of the standard record 12.

The stud 26 is turnably mounted on the bridge 25 by turnably engaging through the bridge and being held against shifting by flanges 28 fixedly mounted on the stud and located adjacent the front and back faces of the bridge. A spiral spring 29 has its inner end attached to the stud 26 and coils about the stud and has its outer end attached to a pin 30 mounted on the bridge 25. An arm 31 is turnably mounted on the stud 26.

A disc 32 has a square opening and engages a square section 33 formed upon the outer portion of the stud 26. Thus the disc 32 is non-rotatively mounted on the stud. A pin 34 projects from the arm 31 and engages one of several openings 35 formed in the arm 31 concentric with the stud 26. A small expansion spring 36 is mounted on the outer end of the stud 26 and acts between the head 37 of the stud and the disc 32 for urging the disc 32 against the arm 31. A

collar 38 on the stud 26 prevents the arm 31 from sliding inwards.

The bottom portion of the arm 31 is provided with a socket 39 supporting the base 40 of a brush having said bristles 27. A screw 41 is mounted on the socket 39 and clamps the base 40 in fixed adjusted positions.

The operation of the device is as follows:

The stylus of the sound box 20 is rested on the edge portion of the new blank record 13. The bristles 27 engage the groove of the standard record 12. The turntable 11 is caused to rotate and one sings or speaks into the horn 14 so that the sound sensitive recording stylus means grooves the new record 13 and simultaneously cuts a recording thereon.

The bristles 27 may be properly engaged with the groove of the record 12 by loosening the screw 41 and slightly extending or retracting the base 40 of the said bristles 27. Moreover, the disc 32 may be moved laterally to disengage the pin 34 from the opening 35 and then the pin 34 may be re-engaged in a different one of the openings 35 which changes the turning urge of the spring 29 upon the arm 31 when the bristles 27 engage the groove of the record 12.

In Fig. 7 a modified form of the invention has been disclosed which distinguishes from the prior form in the fact that a cylindrical projection 45 from the head 37 turnably supports an auxiliary arm 31'. This auxiliary arm 31' is provided with a socket portion 39' supporting the base 40' of an auxiliary brush having bristles 27'. A set screw 41' engages through this socket for holding the base 40' in adjusted positions so that said auxiliary brush bristles may engage the groove of the record 12 at a point adjacent bristles 27. A stud 46 having a central hexagon portion 47 and right and left hand threaded end portions threadedly engages the arms 31 and 31'. Thus these arms 31 and 31' will be caused to move in unison. When desired the stud 46 may be turned to disconnect the arms 31 and 31' so that the arm 31' may be removed.

In other respects this form of the invention is similar to the previous form and like parts are indicated by like reference numerals.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a device for guiding a phonograph sound box across the face of a new record blank from a standard record, a pair of arms extending from said sound box, means clamping the inner ends of said arms in position on said sound box, a bridge between the outer ends of said arms, a stud turnably mounted on said bridge, a follower arm rotatively mounted on said stud and including brush bristles for engaging the grooves of said standard record, means for holding said arm in desired turned positions on said stud, and resilient means for turning said stud to cause said arm to be similarly turned to engage said bristles with the groove of said standard record, said arms being constructed of telescopically engaged sections with means for holding the sections in desired adjusted positions for controlling

the spacing of said brush bristles relative to said sound box.

2. In a device for guiding a phonograph sound box across the face of a new record blank from a standard record, a pair of arms extending from said sound box, means clamping the inner ends of said arms in position on said sound box, a bridge between the outer ends of said arms, a stud turnably mounted on said bridge, a follower arm rotatively mounted on said stud and including brush bristles for engaging the grooves of said standard record, resilient means for turning said stud to cause said arm to be similarly turned to engage said bristles with the groove of said standard record, and means for varying the action of said resilient means on said arm, said varying means comprising a collar on said stud adjacent one side of said arm, a disc slidably but non-rotatively mounted on said arm adjacent the other side of said arm, a pin on said disc selectively engageable with one of a plurality of complementary openings formed in said arm, and means urging said arm and disc against said collar to retain said pin in an engaged position with one of said openings.

3. In a device for guiding a phonograph sound box across the face of a new record blank from a standard record, a pair of arms extending from said sound box, means clamping the inner ends of said arms in position on said sound box, a bridge between the outer ends of said arms, a stud turnably mounted on said bridge, a follower arm rotatively mounted on said stud and including brush bristles for engaging the grooves of said standard record, resilient means for turning said stud to cause said arm to be similarly turned to engage said bristles with the groove of said standard record, and means for varying the action of said resilient means on said arm, said varying means comprising a collar on said stud adjacent one side of said arm, a disc slidably but non-rotatively mounted on said arm adjacent the other side of said arm, a pin on said disc selectively engageable with one of a plurality of complementary openings formed in said arm, and means urging said arm and disc against said collar to retain said pin in an engaged position with one of said openings, said latter means, comprising a head formed on said stud spaced from said disc, and an expansion spring mounted on said stud and operating between said head and disc.

4. In a device for guiding a phonograph sound box across the face of a new record blank from a standard record, a bridge plate supported on the sound box in a position spaced from one side thereof, a stud turnably mounted on said bridge plate and having a free end projecting laterally therefrom, a follower arm mounted on said stud and having brush bristles for engaging the grooves of the standard record, resilient means for turning said stud relative to said plate to cause said bristles to engage the grooves of the standard record, said arm being rotative and slidably on said stud, a collar formed on said stud on one side of said arm, a disc slidably but non-rotatively mounted on said stud on the other side of said arm, releasable means interconnecting said disc and said arm for retaining said arm in various rotative positions on said stud to vary the action of said resilient means in urging said bristles into contact with the grooves of the standard record.

5. In a device for guiding a phonograph sound box across the face of a new record blank from

a standard record, a bridge plate supported on the sound box in a position spaced from one side thereof, a stud turnably mounted on said bridge plate and having a free end projecting laterally therefrom, a follower arm mounted on said stud and having brush bristles for engaging the grooves of the standard record, resilient means for turning said stud relative to said plate to cause said bristles to engage the grooves of the standard record, said arm being rotative and slideable on said stud, a collar formed on said stud on one side of said arm, a disc slidably but non-rotatively mounted on said stud on the other side of said arm, releasable means interconnecting said disc and said arm for retaining said arm in various rotative positions on said stud to vary the action of said resilient means in urging said bristles into contact with the grooves of the standard record, said releasable means comprising a pin extending laterally from said disc toward said arm, said arm being formed with a

10 plurality of openings arranged in a circle concentric with said stud, said pin being engaged with one of said openings, and resilient means on said stud urging said disc into contact with said arm and said arm into contact with said collar to retain said pin in engagement with the opening with which it is engaged.
